(57) **CLAIM**

The ornamental design for a pan, as shown and described.

DESCRIPTION

FIG. 1 is a perspective view of the pan;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a right side view of the pan of FIG. 1 positioned
over a gas stove burner, which is shown in broken lines.

The elements depicted in broken lines in the various figures
are included for environmental purposes only, and form no
part of the claimed design.

1 Claim, 8 Drawing Sheets
